(57) **CLAIM**

The ornamental design for a post lock tool holder for L-shaped wrenches, as shown and described.

DESCRIPTION

FIG. 1 is a front view of a post lock tool holder for L-shaped wrenches showing our new design;

FIG. 2 is a back view thereof;

FIG. 3 is a left side view thereof;

FIG. 4 is a right side view thereof;

FIG. 5 is a bottom view thereof;

FIG. 6 is a top view thereof;

FIG. 7 is a front view thereof, in an opened position;

FIG. 8 is a back view thereof;

FIG. 9 is a left side view thereof;

FIG. 10 is a right side view thereof;

FIG. 11 is a bottom view thereof;

FIG. 12 is a top view thereof; and,

FIG. 13 is a front view thereof.

The broken line showing of the wrenches is included for the purpose of illustrating an environment and forms no part of the claimed design.

1 Claim, 13 Drawing Sheets
